UNITED STATES PATENT OFFICE

CHARLES NORMAN ELSY, OF GLEN ELLYN, ILLINOIS

MANHOLE COVER

Application filed February 13, 1928. Serial No. 253,885.

This invention relates to manhole covers and has among its objects to provide a new and useful cover which shall be simple in construction, durable and readily installed for manholes in road pavements.

An important object of my invention is to provide a manhole cover which shall overcome certain inherent disadvantages in the present or known type of manhole covers. A manhole may be considered as a fixed immovable supporting column for the cover. It is well known that concrete slab pavements settle and that under certain heavy loads, such as when a heavy truck passes over them, will move relatively to the manhole cover and its support, and thus often cause displacement between the concrete slab portions and the manhole covers, thus cracking the slab portions around the manhole covers. It is therefore one of the objects of my invention to provide a manhole cover which shall be supported on the concrete slab and readily movable with it under loading or settlement to thereby overcome any relative displacement between it and the adjacent concrete slab.

Another object of my invention is to provide a manhole cover with means for affording its installation on the proper grade level which means will support the cover at the desired grade level or elevation during the pouring of the concrete road slab around it and yet permit its free movement with the slab under any settlement thereof.

A further object of my invention is to provide a manhole cover having a frame or collar with integral means for supporting it on the road slab.

A still further object of my invention is found in the provision of adjustable means for supporting the manhole cover frame on a supporting ring during its installation and the pouring of the concrete slab around it.

With the above and other objects in view, my invention consists in the novel combination, construction and arrangement of the parts and members shown in my preferred embodiment in the attached drawings, described in the following specifications and

particularly pointed out in the appended claims.

Referring to the illustrations: Fig. 1, is a half elevation and half vertical section showing my new and improved manhole cover. 55

Fig. 2, is a plan view of the cover.

Figs. 3, 4, and 5, are respectively cross sections of the cover plate, frame or collar, and installation supporting ring.

It will be understood that the principles of design herein shown for a cover for a circular manhole may be readily adapted to manhole covers for manholes of any other cross sectional formation. 60

The wall of the manhole is indicated by 65 number 10.

An annular base or ring 11 is provided for mounting upon the top of the manhole wall 10. The ring 11 is of L cross section having a base portion 11^A and a vertically disposed integral wall portion 11^B. Suitable stiffening brackets or lugs 11^C may be cast thereon as shown. The wall portion 11^B is formed with suitably spaced holes 11^P. 70

The cover collar or frame 12 comprises an annular wall 12^A having slots 12^B therein suitably spaced to register with the holes 11^P in the ring 11, and extending upwardly from the lower edge of the frame to a desirable point. 75

The upper edge of the frame 12 is provided with a ledge 12^C for the cover plate 13.

The upper portion of the frame 12 is also enlarged to form an annular rim or flange 12^D. It may here be noted that the rim or flange 12^D might be readily modified in the form of segmental lugs or flange extensions of any suitable formation whereby such frame 12 might be suitably supported upon 85 the concrete road slab 14.

In the installation of my improved manhole cover, the ring 11 is first mounted in place upon the top of the manhole wall 10. Bolts 15 are then placed in the holes 11^P with 95 their heads against the outside of the wall portion 11^B. Then the frame 12 is inserted within the ring 11 with the slots 12^B registering over the bolts 15 and when the frame 12 is properly leveled to the road grade, it is 100

securely retained in place by the tightening of the nuts of the bolts 15.

The concrete slab 14 may then be placed and when the cement has set, the nuts on the bolts 15 may be loosened as the frame 12 will then be supported by means of its flanged upper end 12^b upon the concrete slab.

It will now be readily apparent that whereas the frame 12 is confined within the ring 11 it is free to go up and down with the slab 14 due to the free engagement of the bolts 15 within the slots 12^b.

It will also be noted that the collar or frame may be made of a suitable height adaptable to concrete paving of various thicknesses as the slots 12^b permit its raising and lowering to accommodate varying road levels above the top of the manhole wall. Furthermore, the height of the frame 12 is sufficient to permit a cushion of earth 16 between the bottom of the concrete slab and the ring 11.

While the term "manhole" has been used throughout the above description it is obvious that the same problems exist in other structures than those technically known as "manholes", as for instance in "catch basins" or wherever there is a lined cavity below the paving slab, accessible through an opening in the paving slab which opening is provided with a traffic supporting cover either imperforate or in the form of a grid or the like. It is intended that the term "manhole" as used in the claims shall be construed accordingly.

I claim as my invention:

1. In a structure of the character described, the combination of a surrounding wall structure forming a manhole and containing an opening in its top, a cover-plate-supporting hollow member open at its opposite ends and forming a continuation of the opening in said wall structure and free of support by said wall structure, a concrete slab in which said member is located, and means supporting said member on said slab, said member and slab being capable of downward movement as a unit relative to said wall-structure.

2. In a structure of the character described, the combination of a surrounding wall structure forming a manhole and containing an opening in its top, a cover-plate-supporting hollow member open at its opposite ends and forming a continuation of the opening in said wall-structure and free of support by said wall structure, a concrete slab in which said member is located, means supporting said member on said slab, said member and slab being capable of downward movement as a unit relative to said wall structure, and a mass of relatively yieldable material between said slab and the top of said surrounding wall-structure.

3. In a structure of the character described,

the combination of a surrounding wall structure forming a manhole, a cover-plate-supporting hollow member open at its opposite ends, said wall structure at its upper end and said member telescoping, and said member being free of support by said wall structure, a concrete slab in which said member is located, and means supporting said member on said slab, said member and slab being capable of downward movement as a unit relative to said wall structure.

4. In a structure of the character described, the combination of a surrounding wall structure forming a manhole, an annular positioning ring positioned on the upper edge of said wall structure, a cover-plate-supporting hollow member open at its opposite ends, said ring and said member telescoping and said member being free of support by said wall structure or ring, a concrete slab in which said member is located and vertically spaced from said ring, and means supporting said member on said slab.

5. In a structure of the character described, the combination of a surrounding wall structure forming a manhole, an annular positioning ring positioned on the upper edge of said wall structure, a cover-plate-supporting hollow member open at its opposite ends, said ring and said member telescoping and said member being free of support by said wall structure or ring, a concrete slab in which said member is located and vertically spaced from said ring, means supporting said member on said slab, and a mass of relatively yieldable material between said slab and said ring.

6. In a structure of the character described, the combination of a surrounding wall structure forming a manhole and containing an opening in its top, a cover-plate-supporting hollow member open at its opposite ends and forming a continuation of the opening in said wall structure and free of support by said wall structure, a concrete slab surrounding said member, means in which said member is located on said slab, said member and slab being capable of downward movement relative to said wall structure, and means temporarily supporting said member during assembly of the slab and member.

7. In a structure of the character described, the combination of a surrounding wall structure forming a manhole, an annular positioning ring positioned on the upper edge of said wall structure, a cover-plate-supporting hollow member open at its opposite ends, said ring and said member telescoping and said member being free of support by said wall structure or ring, a concrete slab in which said member is located and vertically spaced from said ring, means supporting said member on said slab, and means temporarily supporting said member in fixed position on said ring.

8. A manhole cover structure comprising,

in combination, a hollow cover-plate-supporting member open at its opposite ends, a ring adapted for support by a manhole structure, means for anchoring said member in a paving slab and serving as the sole support of said member in service, and means for temporarily supporting said member on said ring during the placing of said slab, said last-named means being adapted for release from supporting relation after the placing of said slab.

9. A manhole cover structure comprising, in combination, a hollow cover-plate-supporting member open at its opposite ends, a ring adapted for support by a manhole structure, means for anchoring said member in a paving slab and serving as the sole support of said member in service, and means for temporarily supporting said member on said ring during the placing of said slab, said last-named means being adapted for release from supporting relation after the placing of said slab and said ring and member being adapted for telescopic action in service.

25 In witness whereof I affix my signature.
CHARLES NORMAN ELSY.
